WATER CLOSET FLUSHING APPARATUS

David Zimmerman, Kansas City, Mo., assignor to
Rita Zimmerman, Kansas City, Mo.

Application February 12, 1941, Serial No. 378,622

6 Claims. (Cl. 4—26)

This invention relates to new and useful improvements in water closet flushing apparatus and has as its principal object the provision of means whereby closet bowls can be flushed with a small amount of water under low pressure.

Another important object of the invention is to provide a low pressure flushing apparatus which will afford an economic substitute for the more costly high pressure types of installations now found in general use.

These and various other important objects and advantages of the invention will become apparent to the reader of the following specification.

In the drawings

Figure 1 is a side elevational view of the apparatus.

Figure 2 is a sectional view taken substantially on the line 2—2 of Figure 1.

Figure 3 is an enlarged vertical sectional view taken substantially on the line 3—3 of Figure 2.

Figure 4 is an enlarged fragmentary vertical sectional view taken substantially on the line 4—4 of Figure 1.

Figure 5 is a fragmentary vertical sectional view through the perforated tube of the water container.

Figure 6 is an enlarged cross sectional view taken substantially on the line 6—6 of Figure 3.

Referring to the drawings wherein like numerals designate like parts, it can be seen that numeral 5 denotes a water closet bowl having a flushing conduit 6 leading thereto and in which is a control valve 7.

A reducing T-fitting 8 connects the conduit 6 with the flushing apparatus, the upper end of the T 8 being connected by a nipple 9 with a reducing sleeve 10 at the lower end of an elongated cylindrical water chamber 11 which has brackets 12 thereon whereby the same can be attached to a wall or other support. The upper end of the container 11 is closed by a screw cap 13.

A pipe section 14 extends into the lower end of the fitting 8 and from this pipe section 14 extends an elongated tube 15 which extends upwardly to a point near the cap 13 and then bent backwardly to extend downwardly and terminate adjacent the lower portion of the container 11. As can be seen in Figure 3, this tube 15 is perforated at regular spaced intervals from a point just above the lower end of container 11, to its extremity.

The lower end of the pipe section 14 connects to a T-fitting 16 which, in turn, is connected by a pipe section 17 to a header 18, the latter forming a head for a barrel 19. A second header 20

is provided at the lower end of the barrel 19 thus defining an injector chamber 21.

A short pipe section 22 extends into the lower portion of the header 20 and from this pipe section 22 extends an injector tube 23 which extends upwardly into the barrel 19 and terminates adjacent the upper end thereof.

The lower end of the section 22 connects to a T-fitting 24 to which is connected a supply cut-off valve 26. A pipe section 27 extends downwardly from the fitting 24 to connect to a T-fitting 29 from which extends an air chamber 29, this being in the form of an outwardly extending pipe section connected to an elbow, and, in turn, connected to the elbow is a vertically extending barrel a.

As shown in Figures 2 and 4, an upper chamber 31 is provided and extends from the T-fitting 16, the same consisting of a laterally disposed pipe connected by an elbow to a vertically extending barrel b.

Extending below the fitting 28 is a pipe section 32 which has a drain cock 33 extending laterally therefrom. A cap 34 closes the lower end of pipe section 32.

The function of air chambers 29 and 31 is to prevent water hammer and the resultant noise when valves are opened and closed causing sudden flow and stoppage of water, and to act as reservoirs for water under pressure of compressed air in the top of chambers 29 and 31, this water forming a quick supply for pipe 15 when valve 7 is opened. These chambers 29 and 31 with their reservoirs of water in addition to preventing air hammer tend to keep up the pressure in barrel 11 because they furnish water which does not have to come through supply pipe 30. Upper chamber 11 being filled with air when the apparatus is assembled with valve 26 closed and valve 7 open, when valve 7 is closed and valve 26 open, water from the supply line through pipe 15 enters chamber 11 and compresses the air already in that chamber in the top thereof.

When valve 7 is open water under pressure of compressed air in barrel 11 is forced through pipe 6 to flush the toilet and at the same time water from injector 23 is forced into perforated tube 15 and flows rapidly out of the tube 15 into barrel 11 through the perforations immediately above the water level in barrel 11. The water from tube 15 always flows into barrel 11 from immediately above the water level in that barrel, this preventing any loss of pressure in barrel 11 for two reasons, one being that the water does not have to go to the top of barrel 11, with the

resultant loss of pressure due to the weight of the water column, in tube 15, and secondly, since the water is not introduced into the bottom of barrel 11 or below the water surface the water in barrel 11 going to the toilet is allowed to flow down without interference from entering water in tube 15. By these actions and the function of tubes a-29 and b-31, pressure is maintained in barrel 11 and water rushes out of it through valve 7 with great force.

When valve 7 closes itself, it being a spring valve which closes as soon as sufficient water has passed through it to flush the toilet, and handle is released, the pressure and supply is again quickly built up in barrel 11, and in barrels a-29 and b-31 and the apparatus is ready for another operation almost immediately.

The function of barrel 19 is to form a partial check to water entering tube 15, in this way preventing interference with the entry of water from barrel b-31 which is much more quickly available than water from supply pipe 30.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a device of the class described, a vertically arranged combined air and water chamber, an outlet conduit connected with the lower end of the chamber, a supply pipe and a gooseneck pipe connected with the supply pipe and extending upwardly into the chamber with the bight of the gooseneck located adjacent the top of the chamber, that part of the gooseneck pipe located within the chamber having perforations therein for permitting water to flow from the gooseneck pipe into the chamber above the water level in the chamber, whereby the incoming water will not interfere with the water flowing from the chamber.

2. In a device of the class described, a vertically arranged combination air and water chamber, an outlet conduit connected with the lower end of the chamber leading water therefrom, a gooseneck pipe passing upwardly through the lower end of the chamber with the bight of the gooseneck part located in the upper part of the chamber, those portions of the gooseneck pipe in the chamber having perforations therein for the discharge of water from the gooseneck pipe, means for connecting the lower end of the gooseneck pipe to a supply of water and a vertically arranged air chamber connected with said means between the supply pipe and the gooseneck pipe.

3. In a device of the class described, a vertically arranged combination air and water chamber, an outlet conduit connected with the lower end of the chamber leading water therefrom, a gooseneck pipe passing upwardly through the lower end of the chamber with the bight of the gooseneck part located in the upper part of the chamber, those portions of the gooseneck pipe in

the chamber having perforations therein for the discharge of water from the gooseneck pipe, means for connecting the lower end of the gooseneck pipe to a supply of water and a vertically arranged air chamber connected with said means between the supply pipe and the gooseneck pipe, said connecting means including a vertically arranged barrel located between the air chamber last mentioned and the supply pipe, said barrel acting to check the flow of water from the supply pipe to the gooseneck to permit the water in the second air chamber to pass to the gooseneck.

4. In a device of the class described, a vertically arranged combination air and water chamber, an outlet conduit connected with the lower end of the chamber leading water therefrom, a gooseneck pipe passing upwardly through the lower end of the chamber with the bight of the gooseneck part located in the upper part of the chamber, those portions of the gooseneck pipe in the chamber having perforations therein for the discharge of water from the gooseneck pipe to a supply of water and a vertically arranged air chamber connected with said means between the supply pipe and the gooseneck pipe, said connecting means including a vertically arranged barrel located between the air chamber last mentioned and the supply pipe, said barrel acting to check the flow of water from the supply pipe to the gooseneck to permit the water in the second air chamber to pass to the gooseneck, and an injection tube entering the barrel and spaced therefrom for leading the water from the supply pipe to the barrel.

5. In a device of the class described, a combination air and water chamber vertically arranged, an outlet conduit connected with the lower end of the chamber, a tube passing into the chamber from the bottom thereof and containing perforations, a supply pipe, coupling means connecting the lower end of the tube with the supply pipe, a vertically arranged air chamber connected with the coupling means, a second vertically arranged air chamber, means for connecting the lower end thereof with the junction of the supply pipe with the coupling means and below such junction.

6. In a device of the class described, a combination air and water chamber vertically arranged, an outlet conduit connected with the lower end of the chamber, a tube passing into the chamber from the bottom thereof and containing perforations, a supply pipe, coupling means connecting the lower end of the tube with the supply pipe, a vertically arranged air chamber connected with the coupling means, a second vertically arranged air chamber, means for connecting the lower end thereof with the junction of the supply pipe with the coupling means and below such junction, such coupling means including a barrel located between the first air chamber and the supply pipe and an injection tube extending into the barrel for leading the water from the supply pipe into the barrel.

DAVID ZIMMERMAN.
